UNITED STATES PATENT OFFICE

2,092,037

MECHANICAL PENCIL

Charles E. Wehn, Alameda, Calif.

Application September 9, 1935, Serial No. 39,764

7 Claims. (Cl. 120—18)

This invention relates to mechanical pencils and especially to a pencil of the propelled and repelled type.

The object of the present invention is generally to improve and simplify the construction and operation of pencils of the character described; to provide a pencil which is adapted to receive a removable sleeve containing a lead, crayon, or similar marking material; to provide means for propelling the sleeve, together with the lead carried thereby, from a retracted or repelled position to a writing position, said means being also capable of advancing the lead with relation to the sleeve; to provide means for retracting the sleeve and the lead from writing position; to provide a pencil having a frictional grip on the lead at the tip end thereof and at the same time permitting retraction or repelled action; and, further, to provide a sleeve for enclosing and supporting the lead throughout its length to prevent breakage of the lead at points intermediate its ends.

The pencil is shown by way of illustration in the accompanying drawing, in which—

Fig. 1 is a central, vertical, longitudinal section of the pencil;

Fig. 2 is a longitudinal section of the anchor member;

Fig. 3 is a cross section taken on line III—III of Fig. 1;

Fig. 4 is a cross section taken on line IV—IV of Fig. 1;

Fig. 5 is a perspective view of the driving member;

Fig. 6 is a perspective view of the pusher rod;

Fig. 7 is a perspective view of the lead receiving and supporting sleeve;

Fig. 8 is a section similar to Fig. 1, showing the writing end of the pencil, said view showing the lead in projected or writing position; and

Fig. 9 is a view similar to Fig. 8 showing the lead in retracted position.

Referring to the drawing in detail, and particularly Fig. 1, A indicates the main barrel section of the pencil, B the point or lead carrying section, and C the actuating section. The several sections are disposed end to end and are secured with relation to each other as will hereinafter be described.

Formed in one end of the barrel section is a central passage 2 and secured therein is a tubular member 3, which will hereinafter be referred to as the anchor member. The anchor member is secured in the passage in any suitable manner, for instance by being pressed therein, or otherwise,

and one end of the anchor member projects beyond the barrel section into the actuating section C; the projecting end of the anchor member being provided with an annular shoulder 4 and an internally threaded passage 5 which functions as a nut. The shoulder 4, which is formed on the outer end of the anchor member, secures the actuating section against endwise removal with relation to the anchor member and the barrel A but it permits free rotation of the actuating section. Mounted within the tubular anchor member is a push rod or bar, generally indicated at 6. This bar is flat and its opposite edges are threaded as indicated at 7. One end of the bar is flattened to form a pair of shoulders, as indicated at 8, which engage the nut 5 and as such limits outward movement of the pusher bar. The bar extends through the nut 5 and has threaded engagement therewith, and in order that the bar may be advanced or retracted means must be provided for imparting relative rotational movement between the bar and the nut 5. This is accomplished as follows:

Suitably secured in the actuating section is a driving member consisting of a sleeve 9, one end of which is opened while the other end is partially closed as indicated at 10. A rectangular shaped slot 11 is formed in the partially closed end of the driving member and the pusher rod extends therethrough. The pusher rod is freely movable in an endwise direction with relation to the driving member but the sides of the rectangular shaped slot 11 will engage the flat sides of the pusher rod; hence if the actuating member C and the driving member secured therein are rotated, rotary motion will be transmitted to the pusher bar and as it rotates with relation to the stationary nut 5 the rod will either be advanced or retracted with relation to the point section B, depending upon the direction of rotation of the member C.

The point or lead carrying section B, as previously stated, is carried by the actuating section C, that is the forward end of the actuating section is internally threaded to receive the threaded end 13 of the point section. The point section is otherwise provided with a central passage 14 for the reception of the lead or other marking material to be employed, as indicated at 15.

In the present instance the lead is mounted within an elongated metal sleeve indicated at 16. The sleeve is substantially the same length as the lead and it is made of thin metal and has an annular flange 16a formed at one end. The flange and the sleeve are split from end to end, as indicated

at 17, to permit frictional retention of the lead. A helical spring 18 is interposed between the flange of the sleeve and the threaded end 12 of the point section and its function will hereinafter be described.

5 In actual operation, if it is desired to place a new lead in the point section B, the point section is unscrewed and the sleeve 16, together with the spring 18 is also removed. A new lead is then 10 inserted in the sleeve. The spring 18 is placed in position and the sleeve, together with the lead carried thereby is passed through the spring and inserted in the passage of the point section. The point section containing the sleeve, the lead, and 15 the spring is then screwed back into the actuating section C and by rotating said section in the proper direction the pusher or propelling bar 6 will be advanced. It is of a diameter to permit it to enter the flanged end of the sleeve and it will 20 engage the end of the lead and force it forwardly. The lead, as previously stated, is frictionally held within the sleeve and when pressure is applied on the end of the lead by means of the propeller bar, both the sleeve and the lead will be advanced from 25 the retracted position shown in Figs. 1 and 9, to the advanced or projected position shown in Fig. 8; the spring 18 being brought under compression during such advancement.

The lead is now in a position for writing and if 30 it becomes worn away during writing, it is only again necessary to rotate the actuating section C to move the propeller bar 6 forward. During such forward movement, the lead alone will advance as further forward movement of the sleeve is prevented by the compression of the spring 18. On the other hand, if the individual employing the pencil is through writing and wishes to prevent breaking of the projected lead, he reverses the 35 direction of rotation of the actuating section C causing retraction of the propeller bar 6 and when the bar is retracted spring 18 will expand and, as such, causes retraction of the sleeve and the lead frictionally held therein.

40 From the foregoing it will be noted that a pencil having a frictional grip on the lead at the tip end thereof has been provided which, at the same time, is capable of retracting the lead. It will also be noted that the lead is enclosed by the sleeve substantially from end to end and is thus supported 45 throughout its length and breakage at points intermediate the ends of the lead is prevented.

The pencil structure shown in the present invention was designed with the particular object in view of handling colored leads, such as are commonly referred to as "crayons". These are usually of larger diameter than ordinary pencil leads and they are composed of a colored material and a binder which is oily and fatty in action.

50 A number of mechanical pencils have been constructed for handling colored leads of this character but they have proven a failure for the simple reason that a certain amount of the fatty substance of which the crayon is composed has a tendency to adhere to the inner surface of the lead receiving passage of the pencil. This deposit builds up to such an extent in a comparatively short time that it is almost impossible to force the crayon through and the result is that the propelling mechanism is subjected to excessive strain 55 and wear and the crayon is liable to lodge and thereby permanently plug up the lead receiving passage.

In the present instance when the pencil is used for colored leads, one or more sleeves, such as 60 shown at 16, will accompany a package of leads

and when one sleeve becomes too clogged and dirty it may be thrown away and substituted and any danger of clogging up the lead receiving passage is thus avoided, and excess wear on the propeller mechanism is eliminated.

5 While the pencil, as already stated, is particularly designed for handling crayons, leads and the like, it may obviously be used for ordinary pencil leads and it will be used for that purpose as the mechanism provides a friction tip pencil and at the same time permits retracting action, something that has not been obtainable in pencils where the lead is frictionally held.

10 While certain features of the present invention are more or less specifically described, I wish it understood that various changes may be resorted to within the scope of the appended claims. Similarly, that the materials and finish of the several parts employed may be such as the manufacturer may decide, or varying conditions or uses may demand.

15 Having thus described my invention, what I claim and desire to secure by Letters Patent is:—

20 1. In a pencil of the character described a barrel section, a point section having a passage formed therein and extending therethrough, a removable sleeve insertable in said passage, said sleeve adapted to contain a lead, said sleeve and the lead carried thereby being longitudinally 25 movable in the passage from a retracted position to an advanced writing position, and manually actuated means advanceable or retractable at will, said means being engageable with the lead to advance the lead and the sleeve from a retracted to a projected position, and other means 30 for retracting the sleeve and the lead upon retraction of said manually actuated means.

35 2. In a pencil of the character described a barrel section, a point section having a passage 40 formed therein and extending therethrough, a removable sleeve insertable in said passage, said sleeve adapted to contain a lead, said sleeve and the lead carried thereby being longitudinally movable in the passage from a retracted position to an advanced writing position, and manually 45 actuated means advanceable or retractable at will, said means being engageable with the lead to advance the lead and the sleeve from a retracted to a projected position, and other means for re- 50 tracting the sleeve and the lead upon retraction of said manually actuated means, said means also adapted to project the lead independently of the sleeve when the sleeve assumes a projected position.

55 3. In a pencil having a lead receiving passage formed therein, a removable metal sleeve insertable in the passage, said sleeve adapted to contain a lead and the lead being frictionally gripped within the sleeve, means in the pencil for advancing the sleeve and the lead a predetermined distance and then the lead independently of the sleeve, said means being retractable, and other means for retracting the sleeve and the lead when the retractable means has been retracted.

60 4. In a pencil of the character described a barrel section, a point section having a passage formed therein extending therethrough, a removable sleeve insertable in said passage, said sleeve adapted to contain a lead, an annular 65 flange on one end of the sleeve, a propeller bar in the barrel section, said propeller bar being engageable with the lead in the sleeve, a spring interposed between the inner end of the point section and the flange on the sleeve, said spring 70

being placed under compression when the propeller bar is advanced by movement of the sleeve and lead in unison when pressure is applied by the propeller bar, and means for retracting the propeller bar, said spring simultaneously retracting the sleeve and the lead.

5. A lead holder and carrier for leads such as used in mechanical pencils comprising an elongated open ended sleeve adapted to enclose a lead, said sleeve extending substantially from end to end of the lead and being split longitudinally to frictionally retain the lead but permitting movement of the lead therethrough, and an annular flange formed at one end of the sleeve.

10. 6. In a pencil of the character described, a barrel section, a point section having a passage formed therein and extending therethrough, a removable sleeve insertable in said passage and adapted to contain a lead, said sleeve being circumferentially expandable and having an exterior diameter which is less than the interior diameter of the passage in which it is inserted so that

when the inner surface of the sleeve becomes coated with lead it can expand and maintain a substantially constant frictional grip on the lead, and means for advancing the lead through the sleeve.

15. 7. In a pencil of the character described, a barrel section, a removable point section on the barrel having a passage formed therein and extending therethrough, a removable sleeve insertable in said passage from the inner end of the removable point section, said sleeve adapted to contain a lead and said sleeve being circumferentially expandable and having an exterior diameter less than the interior diameter of the passage in the removable point section, so that when the inner surface of the sleeve becomes coated with lead it can expand and maintain a constant frictional grip on the lead, means for advancing the lead through the sleeve, and means for retaining the sleeve against movement outwardly through the removable point of the pencil.

CHARLES E. WEHN.
